UNITED STATES PATENT OFFICE

2,493,708

LIQUEFIED GAS DISPENSING SYSTEM

Loyd J. White, San Antonio, Tex., assignor to
 Southern Steel Co., San Antonio, Tex., a corporation of Texas

Application October 26, 1938, Serial No. 237,113

4 Claims. (Cl. 62—1)

1

This invention relates to liquefied gas dispensing systems of the type wherein liquid petroleum gas is stored in an underground pressure tank and is vaporized by the heat of the surrounding earth and, among other objects, aims to provide improved means to generate and deliver gas of uniform heating value in systems of the general type disclosed in U. S. Patents Reissue 20,624 and No. 2,121,675. The butane mixtures commonly employed in such systems contain some more volatile constituents, chiefly iso-butane and propane. Most of the mixtures contain from 10% to 25% propane. Normal butane vapor has a heating value of approximately 3274 B. t. u.'s per cubic foot; while propane has about 2619 B. t. u.'s, both at 60° F. and 30 inches mercury column. When a tank is filled, the gas initially generated contains a high percentage of propane vapor because the propane vaporizes first, and the resulting mixture is not as rich as butane vapor. Thus, the gas becomes richer as the supply in the tank is exhausted, because the liquid in the tank contains a progressively higher percentage of butane. This necessitates adjustments of the air supply to the burners of consuming appliances to insure complete combustion. Therefore, the principal object of this invention is to provide a secondary vaporizing chamber to which the liquefied gas is delivered at a reduced pressure from the bottom portion of the tank, whereby to insure the delivery of gas of substantially uniform B. t. u. content and avoid the necessity of adjusting burners to vary the supply of air every time the tank is refilled.

Other aims and advantages of the invention will appear in the specification, when considered in connection with the accompanying drawings, wherein:

Fig. 1 is a sectional view, partly in elevation, showing a system embodying the invention;

Fig. 2 is a sectional view taken on the line 2—2 of Fig. 1;

Fig. 3 is a top plan view, on an enlarged scale, of a combination fitting shown in Fig. 1; and

Fig. 4 is a sectional view taken on the line 4—4 of Fig. 3.

Referring particularly to the drawings, the type of system there shown for illustrative purposes is similar in many respects to that disclosed and claimed in the aforesaid Patent No. 2,121,675. However, it is to be understood that the present invention is applicable to other types of systems, such, for example, as is shown in the aforesaid reissue patent or in Patent No. 2,121,673. In this instance, there is shown an underground pressure

storage tank 10 having a standpipe 11 to which is connected a combination fitting 12 carrying a filling valve 13, vapor return valve 14, safety relief valve 15, pressure gauge 16 and a level gauge 17 adapted to be operated by a float 18, all exactly as disclosed in said Patent No. 2,121,675. These parts and other dispensing appurtenances are housed within a casing 19 similar to that shown in Reissue Patent 20,624.

Instead of dispensing generated gas through the standpipe and the combination fitting 12, as disclosed in Patent 2,121,675, the liquefied gas is delivered from the bottom portion of the tank to a vapor generating chamber or compartment 20 preferably arranged within the tank and shown as having a bottom portion 21 in the form of a semi-circular inverted trough welded to the bottom of the tank to provide additional heat exchanging surface. In cold climates, the pipe 20 may be closed at its lower end and extend through the tank bottom into the ground well below the frost line, where it will absorb more vaporizing heat from the earth. The main part of this chamber may be and preferably is composed of a large piece of pipe welded at its upper end to the upper wall or top of the tank. Liquefied gas is delivered to it from the bottom portion of the tank through an induction pipe 22 extending through the top of the tank, a pressure reducing valve 23 in the casing 19 and a pipe 24 leading back through the tank wall into the upper portion of said chamber, both pipes preferably being welded in the tank wall. The pressure reducing valve is vented to the atmosphere by a pipe 25 leading to the upper part of the casing. The pressure reducing valve lowers the pressure of the fuel within the vaporizing chamber and insures its vaporization by absorption of heat from the contents of the tank, the vaporizing temperature of the fuel at the lower pressure being less than that in the tank. The pressure is reduced to, say, five or ten pounds, gage. Incidentally, the tank pressure ranges from 40 to 50 pounds, depending upon the particular mixture of gas used and the temperature of the tank. The liquefied gas immediately vaporizes in the chamber and the pressure is kept substantially constant.

The gas is delivered from the chamber 20 through a discharge pipe 26 preferably welded in the top wall of the tank and this pipe is shown as having an elbow 27 at its upper end connected to a valve casing 28 carrying a manually operable cut-off valve 29, a branch or service nipple 30 and an excess flow check valve 31. The valve casing is shown as being integral with the com-

bination fitting 12 and corresponds with the service outlet branch shown in Patent 2,121,675 except that the service opening is drilled into the side of the casing to receive the elbow 21 and the casing does not communicate with the hollow interior of the combination fitting. The design is such that the same pattern may be used for casting the present fitting and the one shown in said patent.

A union coupling 32 connects the usual pressure reducing regulator 33 to the outlet branch or service nipple 30. The regulator has the usual vent pipe 34 extending to the upper portion of the casing 19. A service pipe 35 leads downwardly from the regulator to the bottom of the casing and outwardly through the casing wall, adjacent to the top of the tank.

From the foregoing description, it will be seen that the improved system is very simple in its design and easy to assemble. The vaporizer chamber insures a constant supply of dry gas of substantially uniform richness. The gas pressure in the tank serves to force the liquefied gas as it is needed through the reducing valve and the flow will stop when the pressures are balanced against each other.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In a gas dispensing system of the character described having a storage tank, a separate vaporizing chamber within the tank comprising a pipe having an inverted trough-shaped bottom portion welded in the tank; a liquid eduction pipe leading from the bottom portion of said tank into said vaporizing chamber; a pressure reducing valve connected between said eduction pipe and said chamber outside the tank; a discharge pipe connected to said vaporizing chamber to deliver the gas to a service pipe; and filling valves and gauges connected to the tank.

2. In a gas dispensing system of the class described, an underground pressure storage tank in heat exchanging relation with the surrounding earth; a vaporizing chamber within the tank; a liquid eduction pipe leading from the bottom por-

tion of the tank through the tank wall and into the vaporizing chamber; a pressure reducing valve connected to said eduction pipe outside the tank; a gas discharge pipe leading from said vaporizing chamber; control appurtenances connecting said discharge pipe to a service pipe; a protecting casing for said pressure reducing valve and control appurtenances; and a vent for the pressure reducing valve in said casing.

3. In a liquefied petroleum gas dispensing system of the class described, a pressure storage tank adapted to be buried in the ground in heat exchanging relation with the surrounding earth; a liquid eduction pipe leading from the bottom portion of the tank through the tank wall to discharge liquid due to the vapor pressure in the tank; a vaporizing chamber connected to the liquid eduction pipe having a wall constituting a portion of the tank and adapted to absorb heat directly from the earth; a pressure reducing regulator having a valve in said liquid eduction pipe outside of said tank adapted to discharge a mixture of liquid and vapor into said vaporizing chamber; a vapor discharge pipe connected to said vaporizing chamber, and a filling valve connected to the tank.

4. A liquefied petroleum gas dispensing system, as set forth in claim 3, wherein a second pressure reducing valve is connected to said vapor discharge pipe; and said vaporizing chamber is located within the confines of the tank and partially submerged within the liquid contained therein to absorb some vaporizing heat therefrom.
